UNITED STATES PATENT OFFICE.

CHARLES N. SOWDEN, OF GUANTÁNAMO, CUBA.

SWIVEL LAMP-HOLDER.

1,075,952.

Specification of Letters Patent.

Patented Oct. 14, 1913.

Application filed November 1, 1912. Serial No. 728,977.

To all whom it may concern:

Be it known that I, CHARLES N. SOWDEN, a citizen of Canada, at present residing at Guantánamo, Santiago de Cuba Province, Cuba, have invented a new and Improved 5 Swivel Lamp-Holder, of which the following is a full, clear, and exact description.

My invention relates particularly to 10 swivel lamp holders adapted to be mounted on an automobile, locomotive, or other vehicle, and having means whereby the lamp or lamps may be automatically turned in the direction in which the vehicle is turned.

In my invention I provide, in connection 15 with a novel arrangement of the automatic actuating means for turning the lamp from a relatively movable part of the equipage, a manually-controlled acting means; and I furthermore provide for connecting and disconnecting the automatic actuating means, so that said actuating means may respond to the movements of a part of the equipage to which they are connected, but without turning the lamp. I provide for causing the 20 manually-controlled actuating means to make and break the connection between the lamp holder and the automatic actuating means.

Furthermore, in designing the preferred 30 form of the invention it has been my object to improve devices of the general character indicated, to the end that efficiency in operation may be promoted as well as economy of manufacture and simplicity of adjustment and control.

The distinguishing features of my invention, and the important structural elements characterizing the preferred embodiment which is illustrated as an example, will be 40 more particularly explained in the specific description hereinafter to be given.

Reference is to be had to the accompanying drawings forming a part of this specification, in which similar characters of reference indicate corresponding parts in all the views.

Figure 1 is a side elevation, essentially 50 diagrammatic, of a locomotive having my invention applied to the holder and actuating means for supporting and turning the headlight; Fig. 2 is a plan view, largely diagrammatic, of the parts shown in Fig. 1; Fig. 3 is a plan view on a larger scale of the lamp-supporting and actuating means, 55 parts being broken away and others in sec-

tion; Fig. 4 is a longitudinal vertical section of the parts shown in Fig. 3; Fig. 5 is a detail sectional view of one of the drums for the actuating ropes; and Fig. 6 is a front elevation showing the invention applied to 60 a locomotive.

In constructing the illustrated example of my invention, and applying the same to a locomotive, the headlight A may be of any suitable form supported at the front of the 65 locomotive B, the lamp-supporting means including actuating ropes or other flexible elements having connection with the tender C, or other part of the equipage which is movable relatively to the lamp support to 70 automatically turn the light as the locomotive turns. I furthermore provide manually controlled means extending to the cab D of the locomotive whereby the engineer may turn the light and may cause the automatic actuating means to be thrown out of 75 operative connection with the lamp holder.

In the specific form of the invention a bracket 10 has secured thereto a horizontal bed 11, on which is mounted a turntable 12, 80 having suitably secured thereto a platform 13, which receives the headlight A, or other lamp. A spindle 14 in the form of a bolt extends from the bracket 10, through the bed 11, turntable 12 and into or through 85 the platform or base 13 of the lamp, so that the spindle forms the axis of rotation of the turntable and the base 13. On the bed 11 an arm 15 is provided, on the outer end of which a block 16 is supported for trans-

verse sliding movement in an arcuate path; in the form shown the arm has a dovetail groove 15^a and the block 16 a dovetail base 16^a. Secured to the block are operating 90 cords 17, or other flexible elements which extend in the form shown to a drum 18 supported on a bracket 19 on the locomotive B, and in fixed relation to the drum 18 is a larger drum 18^a on which a cord 20 winds, said cord passing over suitable guides or 95 idlers 21 on the locomotive and extending to a suitable connection with the tender C, as indicated at the point 21^a. It will be understood that the connection of the rope 21 may be with any other part of the equipage 100 between which and the locomotive and the lamp there is a relative movement when the locomotive or other vehicle turns to the right or left. Thus, if the locomotive turns 105 to the right, it is obvious that tension will 110

be placed on the cord at the left hand side of the locomotive, and a pull to the left will be given the block 16, so that the headlight A will be turned to the right.

5 In addition to the automatic actuating means a manually-controlled means is provided, consisting of a rope 22 at each side and extending from the cab D within reach of the engineer to a connection with the 10 outer end of the lever 23 fulcrumed as at 24 on the bracket 25 on the turntable 12, at a point intermediate the ends of the lever, one arm 26 of the lever being adapted to control a latch 27 carried by an arm 28 on 15 the turntable 12. The end of the latch is adapted to enter a notch 16^b in the block 16, and from a lug 29 rising from the latch 27, extends a spindle 30 having guided movement in a vertical lug 31 on the arm 28. A 20 spring 32 on the spindle 30 abuts at one end against the lug 31 on the arm 28, the spindle having a nut or nuts 33 for exerting pressure on the outer end of the spring, to regulate its tension.

25 By the described construction, when the latch 27 is in engagement with the block 16, said block is obviously locked to the turntable 12, and is thus in fixed relation to the base 13 of the headlight, so that a pull on 30 either rope 17 in response to a pull on the rope 20 having connection with the tender, will cause the block 16 to slide on the arm 15 and automatically turn the headlight whenever the locomotive turns to the right 35 or left. If, however, a pull is given on either rope 22, which is under the control of the engineer, the first result will be to cause the lever 23 on which the pull is exerted to release the latch 27 from the block 16, by 40 the end of the lever arm 26 engaging the lug 27^a on the latch; the result will be to leave the block 16 free to respond to a pull on either rope 17, without turning the headlight. If a further movement be given the 45 lever 23 by a continued pull on the rope 22, the headlight will be turned by the bodily movement of the lever, and with it, the turntable 12 and the supported headlight.

In order to return the headlight to a neutral position after having been turned in either direction, a spring device is provided, which in this instance consists of a curved coil spring 34 seated horizontally in the upper surface of the bed 11, the said bed having a stop 35 secured thereto, as by a screw 36, the stop being located between washers 37 against which the ends of the spring 34 abut. A depending lug 38 on the under side of the turntable 12 projects downwardly 60 into a groove 35^a in the stop 35 and is adapted to contact with either washer 37, according to the direction of movement of the turntable, so that the turning of the latter in either direction places the spring 34 under 65 compression, giving the same a tendency to

return the headlight to the neutral position with the lug 38 in register with the stop 35.

Desirably ball bearings 39 may be provided between the turntable 12 and the bed 11. It is to be understood, however, that I do not make claim herein to the ball bearings nor to the described arrangement of the spring and stop.

Referring to Fig. 5 and to the left hand side of Fig. 3, the combined drum 18, 18^a, turns around a hub 40, on one end of which is a stud 19^a secured to the bracket 19 by a nut 19^b. A similar stud 19^c on the other side of the hub 40 having a nut 19^d, retains the combined drums in place at the side opposite the bracket 19. At one side of the hub 40 a bearing plate 41 is provided and a pin 42 is employed, passing through the bracket 19, plate 42 and into the hub 40, and securing these parts in fixed relation. Any other suitable means may be employed to rotatably mount the drums. Between the periphery of the hub 40 and the inner periphery of the drum 18^a, I provide a coiled spring 43, fastened respectively to the hub 40 and drum 18^a, as at 43^a, 43^b; the tendency of the spring 43 is to take up any slack in the ropes 17, 20, and keep the same under tension so as to prevent undue slack between the tender and the idlers 21 on the 95 locomotive.

I wish to state in conclusion that although the illustrated example constitutes a practical embodiment of my invention, I do not limit myself strictly to the mechanical details herein illustrated, since manifestly the same can be considerably varied without departure from the spirit of the invention.

Having thus described my invention, I claim as new and desire to secure by Letters 105 Patent:—

1. A lamp-supporting means, comprising a turntable, a support on which said table may turn, a block having transverse movement on said supporting member, flexible elements connected with said block and adapted for connection with parts of a vehicle, to be actuated by the latter, and a latch for establishing connection between the block and the turntable.

2. In a lamp holder, the combination with a support, a turntable on the said support, a member adapted to move transversely on said support, cords connected with said transversely moving member to actuate the same in opposite directions, a latch carried by the turntable and movable into engagement with the transversely moving member to cause said member and the turntable to move in unison, lever devices for releasing the latch, and means for operating said levers.

3. The combination in a lamp holder, of a support having an arm extending therefrom, a turntable adapted to support a 130

lamp, a block mounted to move in an arcuate path on said arm, a latch carried by the turntable, levers extending in opposite directions and adapted to disengage the latch 5 from the block, spring-actuated means tending to engage the latch with the block, operating cords extending in opposite directions from the block and adapted for connection with parts of a vehicle, and manually-controlled cords extending from the 10 said levers.

4. The combination in a lamp holder, of a support, a lamp holder adapted to turn on said support, a movable member on said

support, a latch device normally connecting 15 the lamp holder with the said movable member, a manually-controlled turning means for the lamp holder, and a latch-releasing device operable to release the latch when the said manually controlled turning means is 20 actuated.

In testimony whereof I have signed my name to this specification in the presence of two subscribing witnesses.

CHARLES N. SOWDEN.
